CLAIM

The ornamental design for a spa chaise lounge cushion with face/head support, as shown and described.

DESCRIPTION

FIG. 1 is a perspective view of a spa chaise lounge cushion with face/head support showing my design.

FIG. 2 is a top plan view thereof.

FIG. 3 is a perspective view thereof in an alternate position of use.

FIG. 4 is a rear end, elevational view of FIG. 3.

FIG. 5 is a front end, elevational view of FIG. 3.

FIG. 6 is a left side, elevational view of FIG. 3.

FIG. 7 is a right side, elevational view of FIG. 3.

FIG. 8 is a top plan view of FIG. 3.

FIG. 9 is another left side, elevational view of FIG. 3; and, FIG. 10 is another perspective view thereof in an alternate position of use.

In the drawings, the broken lines represent environmental structure which form no part of the claimed design. The broken lines crossing claimed surfaces in FIGS. 3, 5, 6, 7, 9 and 10 depict claimed stitching.
